(57) CLAIM

The ornamental design for a sports training device, as shown and described.

DESCRIPTION

FIG. 1 is a perspective view of a sports training device showing our new design;

FIG. 2 is an alternative perspective view of FIG. 1;

FIG. 3 is a front elevation view of FIG. 1, the rear elevation view being a mirror image thereof;

FIG. 4 is a side elevation view of FIG. 1;

FIG. 5 is an opposite side elevation view of FIG. 1;

FIG. 6 is a top plan view of FIG. 1; and,

FIG. 7 is a bottom plan view of FIG. 1.

The broken lines in the figures illustrate portions of the article that form no part of the claimed design.

“Rapsodo” shown in broken lines and forming no part of the claimed design is a registered trademark of RAPSODO PTE. LTD., Singapore City, Singapore.
